UNITED STATES PATENT OFFICE

FREDERICK T. HUGHES, OF LOS ANGELES, CALIFORNIA

NONPICKABLE KEYHOLE LOCK

Application filed April 4, 1927. Serial No. 180,789.

This invention relates to a lock attachment of the type which has come into use and which is inserted in an ordinary key hole in a door. These lock attachments are miniature pin tumbler or cylinder locks. They are thrust into the key hole from one side of the door and are usually provided with a spring-pressed dog which becomes extended or projected from the stem of the device after it is placed in the key hole, and this dog operates to prevent the withdrawal of the miniature lock. In this way, an ordinary lock which can be opened by a simple ward-type key can be transformed into a pin tumbler lock, because it requires a small pin tumbler lock key to remove the inserted miniature lock before the door can be opened with the regular key. The dog which is used on the stem of such a miniature lock is usually provided with an inclined face or edge which, when the miniature lock is inserted, engages the upper edge of the key hole and is moved down or folded into the stem of the inserted lock so as to permit the inserted lock to pass into the key hole; this dog is spring-pressed, and as the inserted lock is shoved "home" in the key hole, the dog springs up behind a part of the regular lock of the door and prevents the inserted lock from being removed except by the use of the pin tumbler type key inserted in the miniature lock. When this pin tumbler type key is inserted, the stem of the inserted lock can be rotated so as to swing the dog down into a position which will enable the dog to permit the withdrawal of the inserted lock. The presence of this inclined edge on the dog, however, renders it possible to "pick" such a lock, and this is accomplished by inserting an instrument from the side of the door opposite to that at which the miniature lock is inserted. The instrument can be moved along until its ends strike the inclined edge of the dog and in this way the dog can be moved down into its folded or retracted position, after which the inserted lock can be shoved out of the key hole. The general object of this invention is to overcome this difficulty and to produce a key hole lock of this type which can not be "picked" in the manner suggested. More specifically stated,

the principal object of the invention is to provide such a key hole lock with a detent dog for holding it in the door, constructed in such a way that it can not be manipulated by any instrument inserted from the outside of the door in such a way as to retract the dog or fold it into its retracted position.

Further objects of the invention will appear hereinafter.

The invention consists of the novel parts and combination of parts to be described hereinafter, all of which contribute to produce an efficient non-pickable key hole lock.

A preferred embodiment of the invention is described in the following specification, while the broad scope of the invention is pointed out in the appended claims.

The drawing is a vertical section through a portion of a door at the key hole and illustrating a key hole lock of the type referred to inserted in the key hole. This view shows a portion of the tubular stem of the key hole lock broken away so as to illustrate the preferred construction of the detent or dog.

Referring more particularly to the parts, 1 represents one of the plates of a regular door lock which is used in connection with a regular ward-type key. This regular lock is mounted in the middle plane of the door 2, the outer faces of the door being provided with escutcheons 3.

The key hole 4 is formed through the door and through these escutcheons in the usual way.

The key hole lock embodying my invention is constructed so as to enable it to be slipped into the key hole in the usual manner from one side of the door; and it is provided with a retractable detent to engage a part within the door to prevent withdrawal of the lock. According to my invention I give this detent a contour which will operate to prevent it from being retracted to disengage it from the door by an instrument inserted from the other side of the door. The detent is preferably constructed so that, when the lock is inserted in the key hole, it moves laterally outwardly from the axis of the key hole, so as to engage a part of the door, for example, the plate 1. The key hole lock is

provided with key controlled means for effecting the rotation of the detent on the axis of the key hole into a position which will permit the withdrawal of the key-hole lock.

In the present embodiment of the invention, the key hole lock comprises a casing 5 which has the general contour in cross section of the key hole, that is to say, its upper end is formed into a barrel 6 and its lower portion is formed into a "block" 7 which carries 10 the sliding pins 8 of the key hole lock. Within the barrel 6 the inner portion 9 of a stem 10 is rotatably mounted. By inserting a key 11, the wavy edge of the key will hold the pins 8 in the proper position to enable the stem 9 to be rotated.

The stem 10 of the lock is provided with a retractable detent or dog 12 which is preferably mounted to move laterally in a transverse slot 13 in the stem. The stem 10 is preferably tubular and the detent or dog 12 is spring-pressed toward its extended position in which it is illustrated. This may be accomplished by means of a coil spring 14 mounted in the end of the stem 10 beyond the dog 12. The dog is mounted to rotate on a pivot pin 15 and its end is provided with a cam edge 16. In the end of the stem 10 beyond the dog, a ball 18 is provided which 30 is held against the cam edge 16 by the spring 14. This holds the detent 12 normally extended but permits it to be forced inwardly.

The inner end of the "block" 7 of the key-hole lock casing is formed into a guide shoe 25 or spur 19 which projects forwardly and guides the lower end of the key-hole lock as it is thrust into position. The dog 12 projects upwardly from the stem 10 as indicated and is provided with an inclined face 40 or edge 20. When the key-hole lock is being inserted in the key hole, this edge 20 strikes the upper edge 21 of the key hole in one of the escutcheons 3 and this swings the dog down into its retracted position. When the inserting movement is completed, the spring 14 swings the dog 12 up so that it projects above the edge 22 of the opening in the plate 1. When this occurs, a shoulder 23 on the casing 7 of the key-hole lock will have engaged the outer face of the plate 1. In this way the dog and the shoulder 23 cooperate to prevent the key-hole lock from being removed.

In order to remove the key-hole lock to permit the regular key to be inserted, it is simply necessary to insert the key 11 and rotate it. This will rotate the stem 10 so as to bring the dog 12 down into a lower position in line with the lower portion of the key hole. After 60 this has been done, the key-hole lock can be readily withdrawn and will pull out of the key hole with the key 11.

According to my invention, I give the detent a contour such that an instrument inserted in the key hole cannot retract the de-

tent, that is, from the outer end 25 of the key hole. In other words, I make the inclined face inaccessible by constructing the detent so that such an instrument can not be brought into contact with the inclined edge. In the present embodiment, this inclined edge 20 does not extend from the outer portion of the dog inwardly until it reaches the side of the stem, but the inner portion 24 of this inclined edge or face is cut away so as to produce a recess in the form of an undercut notch 26 at this point. With a dog embodying my invention, if an instrument is inserted at the point 25 and above the stem 10, its end can not come into contact with the inclined edge 20 and the undercut notch 26 when engaged by such an instrument is incapable of swinging the dog sufficiently to extract it. Hence, the insertion of such an instrument can not move the dog down so as to clear the edge 22 and permit the key-hole lock to be forced out of the key hole.

It is understood that the embodiment of the invention described herein is only one of the many embodiments this invention may take, and I do not wish to be limited in the practice of the invention, nor in the claims, to the particular embodiment set forth.

What I claim is:

1. A non-pickable key-hole lock constructed to be slipped into the key hole from one side of the door and having a detent to engage a part within the door to prevent withdrawal of the lock, said detent having a contour operating to prevent the same from being disengaged by an instrument inserted from the other side of the door.

2. A non-pickable key hole lock constructed to be slipped into the key-hole from one side of the door and having a movable detent to engage a part within the door to prevent withdrawal of the key-hole lock, and key controlled means for moving the detent into a position to permit the withdrawal of the lock, said detent having a contour at its inner end incapable of moving the detent and operating to prevent the same from being disengaged from the door by an instrument inserted in the key hole from the other side of the door.

3. A non-pickable key hole lock constructed to be slipped into the key hole from one side of the door and having a detent mounted for rotation on the axis of the key hole and movable laterally with respect to the axis of the key hole to engage a portion of the door when the key hole lock is inserted, and thereby prevent withdrawal of the lock, said detent having a contour adjacent its inner end operating to render it incapable of being moved radially inwardly toward the axis of the key-hole by an instrument inserted from the other side of the door.

4. A non-pickable key-hole lock having a casing constructed to be slipped into the

key-hole from one side of the door and having a stem rotatably mounted in the casing, a laterally movable retractable detent carried by the stem constructed to engage a portion of the door when the key hole lock is being inserted and thereby prevent withdrawal of the lock, and key-controlled means for effecting the rotation of the stem to move the detent into a position to permit withdrawal of the lock, said detent having a contour adjacent its inner end rendering the same incapable of being moved on the stem by a force engaging its inner end adjacent the stem, thereby preventing the same from being moved inwardly toward the axis of the stem by an instrument inserted from the other side of the door.

5. In a non-pickable key-hole lock, the combination of a lock casing constructed to be slipped into the key hole from one side of the door, a retractable detent having a face operating to engage a portion of the key hole to retract the detent when the lock casing is being slipped into the key hole, said detent 20 operating to engage a part within the door to prevent withdrawal of the casing, said face being located to one side of the key-hole, and in a position to be inaccessible to an instrument inserted through the key hole from 25 the outer side of the door.

6. In a non-pickable key-hole lock for a door, the combination of a lock casing constructed to be slipped into the key hole of a door lock from one side of the door and having 30 a stem projecting at one end of the casing toward the other side of the door, a spring-pressed dog carried by the stem for engaging a part within the door to prevent withdrawal of the lock casing from the key hole, said dog having an inclined face operating to engage a portion of the key hole and retract the dog when the lock casing is being slipped into the key hole, said dog having a recess in a position to be engaged by an 35 instrument thrust into the key hole from the opposite side and operating to prevent said instrument from engaging the inclined face to retract the dog.

7. In a non-pickable key-hole lock for a key hole in a door, the combination of a lock casing constructed to be slipped into the key hole of the door lock from one side of the door and having a stem projecting at one end of the casing toward the other side of the door, said stem having a transverse slot therein, a spring-pressed dog carried by the stem in the slot and operating to engage a portion of the door lock to prevent withdrawal of the lock casing from the key hole, 55 said dog having an inclined face operating to engage a portion of the key hole and retract the dog when the casing is being slipped into the key hole, said inclined face being located at a point removed from the adjacent 60 side of the stem and in a position in which it

cannot be engaged by an instrument thrust into the key hole from the opposite side, said dog having a form at its inner end rendering the dog incapable of retracting rotation.

8. A non-pickable keyhole lock constructed to be slipped into the key hole from one side of the door and having a detent to engage a part within the door to prevent withdrawal of the lock, said detent having a contour adjacent its inner end operating to prevent the detent from being disengaged by an instrument inserted from the other side of the door.

9. A non-pickable keyhole lock constructed to be slipped into the keyhole from one side of the door and having a detent to engage a part within the door to prevent withdrawal of the lock, the key control means for rotating the detent into a position to permit the withdrawal of the lock, said detent having an inclined edge facilitating its passage into the keyhole, said inclined edge having a contour adjacent its inner end operating to prevent the inclined edge from being engaged by an instrument inserted in the keyhole from the other side of the door.

Signed at Los Angeles, Calif., this 18th day of March, 1927.
